OVERWIND PREVENTER FOR TIMEPIECE

Friedrich Meyer, Grenchen, Switzerland, assignor to
Felsa A. G., Grenchen, Switzerland

Application May 15, 1951, Serial No. 226,361

Claims priority, application Switzerland March 14, 1951

2 Claims. (Cl. 58—83)

My invention relates to timepiece movements and particularly to a movement with an automatic winding mechanism including a lockable oscillating weight.

As is well-known to those skilled in the art in timepiece (watches, clocks etc.) with automatic winding mechanisms, provisions must be made to prevent the overwinding of the motor spring.

In almost all of the prior devices for limiting the winding up of timepieces, constructions are used depending upon friction produced by a spring. However, the effect of such springs largely depends on outer, uncontrollable influence, such as changes in climate and in temperature affecting the degree of winding of the motor spring. In most cases a bridle in the barrel is used for this purpose. However, a bridle may, under large changes in temperature, influence the motor spring in such a way that the spring is wound to only half the desired value so that the timepiece may have a reserve of power of only ten to twenty hours.

Also snap mechanisms for a positive locking of the oscillating weight have been used, these mechanisms being under the constraint both of the motor spring and of a counterspring, whereby on an excess of the force of the motor spring beyond the force of the counterspring, a locking member snaps engagement with the oscillating weight. However, these countersprings relax with time as they are permanently loaded by the motor spring.

It is an object of my invention to provide a timepiece movement in which the device for locking the oscillating weight is controllable by a differential gear in operating connection with the barrel and the barrel arbor in such a way that the device stops the oscillating weight after a prescribed winding rotation of the motor spring and releases the weight after a prescribed developing rotation of the motor spring.

Bridles and countersprings are necessary in the movement in accordance with the invention and the winding limit remains the same during the entire life of the movement and under changes in temperature.

A further object of my invention is to provide a snap mechanism as a locking device to positively engage the oscillating weight.

Another object is to provide a movement in which the differential gear bends a spring in both directions of rotation of a driven member so that the spring releases a snap lever then swung by the spring, the lever locking the oscillating weight in the one direction of rotation of said driven member and releasing the weight in the other direction of rotation of said driven member.

Other objects and features of the invention will be apparent as the following description proceeds, reference being had to the accompanying drawings, illustrating by way of examples, two embodiments of my invention, and wherein

Fig. 7 is a section along the line I—K of Fig. 6.

10 A pinion 2 is rigidly connected with the barrel 1, while a pinion 3 of the same diameter and number of teeth as pinion 2 is rigidly fixed to the barrel arbor 4. The pinion 2 is permanently in mesh with the drive wheel 5 loosely mounted on a shoulder 6 of the pillar plate 7 while the pinion 3 engages a drive wheel 8 of the same diameter and number of teeth as wheel 5. Wheel 8 coaxial to wheel 5 is in rigid connection with a sun wheel 9 and, together with the latter, revolvably mounted on the sleeve 10 which rotates around a pin 11 fixed to the pillar plate 7. The sun wheel 12 is rigidly fixed to the sleeve 10. Two intermeshing planet wheels 13 having equal diameters and numbers of teeth are revolvably mounted on the drive wheel 5. The one of these planet wheels engages the sun wheel 12 and the other the sun wheel 9. A disk 14 with a cam 15 is rigidly attached to the sleeve 10 constituting the driven member of the differential gear. A pinion 18 is fixed to the outer end of the sleeve 10 and drives a hand 17 by means of a toothed wheel 16, the hand 17 indicating the development condition or degree of tension of the motor spring (not shown) located in the barrel 1. According as the barrel arbor 4 is driven by the oscillating weight 18 with the aid of means not shown, or the barrel 1 is rotated by the developing motor spring, the differential gear rotates disk 14 with cam 15 either in the anticlockwise or clockwise direction of Fig. 1.

A lever 20 is revolvably mounted on a pin 19 of the pillar plate 7 at such a friction resistance that it cannot rotate by itself. A spring 22 is attached on the collar 21 of the lever 20. The collar 21 is flattened as at 39 (Fig. 3) and the wall of the hole of spring 22 has a corresponding even portion so that the spring 22 cannot turn relatively to the lever 20. The lever 20 is at the same level with the control cam 15 of disk 14 so that it can be operated by said cam in a manner described later on. The spring 22 comprises two portions 23 and 24 which, in relieved condition, are practically straight-lined. They are connected with each other by a curved portion 25 which provides for a favorable deformability of the spring 22. The portion 23 of spring 22 traverses with play an opening 26 of the flattened portion 27 of a pin fixed to the locking or snap lever 28, this pin permanently coupling the spring 22 with the lever 28. The latter is pivoted on the pillar plate 7 by means of the pin 29. Pin 29 carries a stop pin 30 against which abuts the end of spring 22 from the one side (Fig. 1). Lever 28 is formed with a bend as indicated at 31 and its free end lies at the level of the oscillating weight 18. This free end has two recesses 32 and 33 and the oscillating weight 18 carries at its ends pins 34 and 35 respectively. Recess 33 and pin 34, as well as recess 32 and pin 35 form each the halves of two couplings, engaging each other for locking the oscillating weight 18. The snap lever 28 has stop faces 36 and 37 to cooperate with the pin 34 or 35 respectively in order to return the snap lever 28, which has before been swung by the spring 22 in the anticlockwise direction, in the clockwise direction far enough to allow either the pin 34 to engage the recess 33 or the pin 35 to mesh with the recess 32.

The shown and described device operates as follows:

With reference to Fig. 1 the snap lever 28 is in locking position and the pin 34 engages the recess 33. There-

fore, the weight 18 cannot oscillate. The motor spring develops and thereby the barrel 1 turns the disk 14 with cam 15 in the clockwise direction in Fig. 1 by means of the differential gear. In Fig. 1 the cam 15 already abuts against the lever 29 and swings the latter in the anticlockwise direction. The spring 22 rests against the stop 30, but is not yet deflected. On further movement of lever 20 the spring 22 cannot turn in the anticlockwise direction in Fig. 1, since it butts against stop 30. Therefore, it is now being deflected in that it is bent towards the right in Fig. 1. The play of spring 22 in the opening 26 of the part 27 is sufficient to prevent the deflection from having an undesired influence on lever 28 so that the recess 33 cannot be moved out of reach of the pin 34. After a certain increase of the deflection of spring 22 owing to the movement of lever 20 under the action of cam 15, the spring 22 slides off the stop 30 and it is free to relieve. On returning into unstressed condition the spring swings lever 28 suddenly in the clockwise direction of Fig. 1 until lever 28 strikes against an external stop not shown. The recesses 32, 33 and the stop faces 36 and 37 of lever 28 go out the path of the pins 34 and 35 of the oscillating weight 18. The weight 18 can now oscillate and wind up the motor spring in the barrel 1. While the above phenomena occurred, cam 15 became free to pass by the lever 29 into the right-hand chain-dotted end position of Fig. 1. After lever 28 having struck against the external stop (not shown) the spring 22 has completely stretched itself and thereby slightly returned the lever 20 in the clockwise direction so that its free end lies again in the path of cam 15. The cam 15 is now on the right of lever 20 and spring 22 lies at the opposite side of stop 30.

As the oscillating weight 18 winds now up the motor spring, the barrel arbor 4, by the aid of the differential gear, turns the disk 14 back in the anticlockwise direction of Fig. 1. Cam 15 butts against the lever 20 from the right in Fig. 1, swings it in the clockwise direction and presses spring 22 against the stop 30. Therefore, for the time being, spring 22 cannot move lever 28 out of non-locking position in the anticlockwise direction and it is being bent in the opposite direction than before, i. e., towards the left in Fig. 1. When a certain deflection is reached, the spring 22 can slide off the pin 30 from right to left in Fig. 1 whereupon it stretches itself and suddenly throws lever 28 back in the anticlockwise direction until lever 28 rests against an internal stop not shown. Now, lever 28 lies in the path of the pins 34 and 35. According to the momentary position of the oscillating weight 18 on the sudden movement of lever 28, either pin 34 strikes against the face 36 or the pin 35 against the face 37 and slightly returns lever 28 in the clockwise direction against the constraint of spring 22 until pin 34 or 35 respectively comes into reach of recess 33 or 32 respectively, whereupon the spring 22 suddenly throws lever 28 back in the anticlockwise direction so that either pin 34 engages recess 33 or pin 35 meshes with recess 32. While these phenomena occurred, cam 15 has passed by the lever 20. After the lever 28 having struck against the internal stop (not shown), the spring 22 has completely stretched itself and has thereby slightly moved back the lever 20 in the anticlockwise direction so that its free end lies again in the path of the cam 15. The described cycle is now repeated.

Since cam 15 positively driven by the differential gear operates lever 28 by means of spring 22 always after the same prescribed value of the winding or development rotation of the motor spring, winding up and developing of the latter always to the same limit is guaranteed inde-

pendent of the outer conditions. There is no friction device, no bridle or counterspring subjected to outer influences (climatic and the like). Lever 23 is not under the effect of the motor spring, but under the constraint of spring 22 whose deflection merely depends on the path of cam 15, which is always the same. The shown and described device allows for the first time timepieces with automatic winding mechanism to be made, which work reliably at any change in climate and temperature. Moreover, winding mechanism and barrel are conserved and this fact results in an increase of life of delicate parts.

Figs. 6 and 7 show another shape and position of the snap lever 28a. While in the example of Figs. 1 to 4 the recesses 32 and 33 are provided on that end of the two-armed lever 28, which is turned away from the disk 14, the coupling half of the one-armed lever 28a of Figs. 6 and 7 is in the shape of a pin 40 mounted on that end of lever 28a which is turned towards the disk 14. According to the momentary position of the oscillating weight 18, the other coupling half is constituted by one of several recesses 41 distributed along the inner edge of the weight 18. The fact of providing several recesses 41 offers the advantage of the latter, after arrival of lever 28a in locking position and at certain momentary positions of the oscillating weight, being stopped quicker than in the first embodiment where coupling halves are only provided on the ends of the oscillating weight.

While I have shown and described two examples of my novel device, I do not wish to unnecessarily limit the scope of my invention, but reserve the right to make such modifications and rearrangements of the several parts that may come within the purview of the accompanying claims.

What I claim is:

1. An overwind preventer for a timepiece comprising oscillating weight winding mechanism including a barrel and a barrel arbor, a differential gear operatively connected between the barrel and the barrel arbor, locking means for the oscillating weight, a spring, a stop for the spring, operating means connected with the differential gear to move the spring past the stop, and a snap action locking lever swung by the spring locking the oscillating weight in the one direction of the differential gear and unlocking the oscillating weight in the opposite direction of the differential gear.

2. An overwind preventer for a timepiece comprising oscillating weight winding mechanism including a barrel and a barrel arbor, a differential gear operatively connected between the barrel and the barrel arbor, locking means for the oscillating weight, a spring, operating means connected with the differential gear to move the spring, a snap action locking lever for the oscillating weight, the spring permanently coupled with the snap action locking lever, and a stop positioned within the axis of rotation of the locking lever, the spring adapted to contact the stop and bend to thereby pass the stop whereby the locking lever is moved to and away from the oscillating weight depending upon the direction of rotation of the differential gear.
